UNITED STATES PATENT OFFICE.

MICHAEL G. MANDT, OF STOUGHTON, WISCONSIN, ASSIGNOR OF ONE-FIFTEENTH TO E. K. LOVERUD AND ONE-HALF TO CHRIS OLSON, OF STOUGHTON, WISCONSIN

CONCRETE BUILDING-WALL.

No. 901,017.

Specification of Letters Patent.

Patented Oct. 13, 1908.

Application filed May 11, 1905. Serial No. 259,998.

To all whom it may concern:

Be it known that I, MICHAEL G. MANDT, a citizen of the United States, residing at Stoughton, county of Dane, and State of Wisconsin, have invented new and useful Improvements in Concrete Building-Walls, of which the following is a specification.

My invention relates to improvements in concrete building walls and it pertains both to the construction of the concrete building blocks and to the peculiar combination and arrangement of such blocks when laid up in the wall.

The construction of my invention is explained by reference to the accompanying drawings in which

Figure 1 represents a perspective view of a wall formed of my improved blocks. Fig. 2 represents a top view of one of the blocks removed from the wall. Fig. 3 represents a top view of two courses of building blocks as arranged in the construction of the wall. Fig. 4 represents a top view of a single course of blocks showing their arrangement and construction when used in connection with a window frame. Figs. 5 and 6 represent special forms of blocks used at the corner of a building, as indicated in Fig. 1.

Like parts are identified by the same reference figures throughout the several views.

All of the building blocks comprising both the front and rear surfaces of the main body portion of the wall are of like construction and they are formed with flat top and bottom faces 1, 1, straight vertical faces 2, 2, hollow V-shaped projections 3 formed upon their rear vertical sides, comprising the two inwardly converging walls 4, 4 which connect with the exterior wall 5 at a distance from its respective ends, whereby a triangular opening 6 is formed between said front wall 5 and the two converging walls 4, 4. By this construction, the triangular shaped opening 6 serves for the circulation of the air between the front and rear walls, while the V-shaped projections of the respective front and rear walls extend across the intermediate space and bear against the inner surfaces of the blocks of the opposing wall, whereby said front and rear courses of blocks mutually strengthen and support each other.

Attention is called to the fact that by connecting the angular walls 4, 4 with the front wall 5 at a slight distance from its end, when said blocks are laid up in courses as indi-

cated in Fig. 1, open spaces 7 are left between the opposing surfaces of the V-shaped projections of the respective front and rear courses, which spaces correspond in width to the distance between the obtuse angles 8, 8 and the ends of the blocks 9. While it is obvious that if said V-shaped projections of the blocks of the respective courses were extended to the ends of the respective blocks there would be no spaces left between said angular surfaces, but instead, the opposing angular surfaces would be brought in contact. Thus it will be obvious that when the several blocks are laid in courses, as indicated in Figs. 1, 3 and 4, a plurality of zigzag spaces 70 are formed between the respective front and rear courses throughout the entire wall, while a plurality of triangular spaces 6 are formed in the respective blocks.

It will be understood that when the blocks are arranged in courses so that the joints between the blocks of one course are arranged to break joints with the next adjacent courses, the V-shaped or angular projections 3 of one course will overlap and rest upon the V-shaped or angular projections of the next adjacent courses as indicated in Fig. 3, whereby the blocks of the front and rear surfaces are interlocked and serve to bind the front and rear surfaces together.

For convenience in construction, I preferably provide two additional forms of building blocks indicated in Figs. 5 and 6. Fig. 5 comprises the vertical walls 10 and 11, diagonal wall 12 and rectangular wall 13, said block being provided with an open triangular space 14 extending between its upper and lower surfaces. The block shown in Fig. 6 comprises the vertical walls 15 and 16 and diagonal wall 17, while the block is provided with an open triangular space 18. The block shown in Fig. 5 is adapted to turn the corner of the exterior course of blocks, as shown at 19, while the block shown in Fig. 6 is adapted to turn the corner of the interior course, as shown at 20.

Where the wall abuts against the window casing 22, as shown in Fig. 4, I preferably provide the same with the peculiar shaped blocks 23, 23, one of the vertical ends of which abuts against the next adjacent block 2 in the course, while their opposite ends 24, 24 are adapted to bear against the window casing, as shown in Fig. 4.

The blocks 23 are respectively provided

with V-shaped projections 25 between which and the window casing a rectangular space 26 is left for the window weights 27 with their weight-supporting ropes.

5 Having thus described my invention what I claim as new and desire to secure by Letters Patent is,—

1. A concrete building wall comprising a plurality of blocks laid in courses one above another, the several blocks of such courses having parallel vertical front and rear surfaces and provided with a hollow projection, which projection is connected at its ends with the rear surface of said block at a distance from its respective ends, the projections of one course laid in overlapping and interlocking relation with the projections of the preceding and next succeeding courses, whereby a plurality of registering air passages are formed through the overlapping hollow projections of the front and rear blocks of the successive courses.

2. In a concrete building wall; the combination of a plurality of building blocks each

comprising an exterior wall and two rearwardly converging walls each connected with the exterior wall at a distance from its end, the hollow projection of the block in one face of the wall registers with the hollow projection in the overlapping blocks in 30 the opposite face of the wall, an exterior corner block comprising the vertical walls and diagonal wall with an open space; interior corner block comprising the vertical walls and diagonal wall, said blocks being 35 provided with an open space, the angular projections of the blocks of one course being adapted to overlap and interlock with the angular projections of the blocks of the next adjacent course, all substantially as 40 and for the purpose specified.

In testimony whereof I affix my signature in the presence of two witnesses.

MICHAEL G. MANDT.
